AIRCRAFT TUBING RATCHET WRENCH

Gerald MacLendon Gutowski, Baltimore, Md.

Application October 24, 1947, Serial No. 781,870

2 Claims. (Cl. 81—91)

1

This invention relates to wrenches, and more particularly to a wrench of the ratchet type having movable jaws adapted to engage a nut or similarly shaped fitting.

The invention is especially adapted for use in assembling and disassembling aircraft tubing connections, for which purpose a wrench is needed which can be rapidly operated and automatically adjusted to nuts and couplings. It will be understood, however, that the invention is not limited to such use, and is capable of application to a wide variety of operations requiring a tool of the character described.

The invention has for its chief object the provision of a ratchet wrench having pivoted jaws, one of which is spring-pressed, to provide for automatic adjustment of the wrench to a nut.

A further object of the invention is to provide a ratchet wrench having opposed pivotal jaws mounted for operation on a single pivot so positioned as to promote easy operation of the wrench, and increase the mechanical advantage of the same, while, at the same time reducing to a minimum the strain on the pivot.

A still further object of the invention is to provide a wrench of the type referred to of simple design and rugged construction, having few parts and capable of being readily taken apart for purposes of replacement and repair.

The above and other objects and advantages of the invention will be apparent from the following description, constituting a specification of the same, when taken in connection with the accompanying drawings, wherein:

Figure 1 is a side elevational view of the wrench showing the relative positions of the parts of the same when applied to a nut.

Figure 2 is a front elevational view of the wrench.

Figure 3 is a side elevational view of the same, partly in section, taken along the line 3—3 of Figure 2, looking in the direction indicated by the arrows, and showing the internal arrangement of the parts.

Figure 4 is a fragmentary rear view of the wrench.

Figure 5 is a cross-sectional view of the same taken along the line 5—5 of Figure 3, looking in the direction indicated by the arrows.

Referring to the drawings in greater detail, I indicates the handle of the wrench, which, in the present instance, is of circular cross-section, but which may be of any other convenient shape. The handle is formed with an enlarged head por-

2

tion 2 at one end, which serves as a housing and support for the movable jaws 4 and 5.

The head portion 2 is open at its front, rear and outer end, and is preferably of a width not exceeding that of the handle, so that the wrench has a more or less flat shape for introduction into places where the available space is limited. The sides of the head portion are joined across the front by a bridge 1, which extends outwardly beyond the end of the housing to form an abutment 8 for engagement with a projection on 9 formed on the jaw 5.

The movable jaw 4 is of a width to fit snugly within the head portion 2, and is formed with spaced-apart extensions 11 and 12, which are perforated to receive a pivot pin 14, and which receive between them the perforated end portion 15 of the opposing pivoted jaw 5. The jaw 4 has a curved outer portion 16 provided with notches 17 for engagement with the corners of a nut. The lower end of the jaw 4 is formed with an extension 18 having a cam-like portion 19 adapted to engage a leaf spring 21, which is secured to the handle by a screw 22.

The jaw 5 is also somewhat curved, and is provided with notches 23 identical with the notches 17 of the jaw 4, and serving the same purpose.

It will be noted that the spring 21 is bent to permit the free end of the same to extend into the head portion 2 to engage the portion 19 of the jaw 4, so that the free end of the spring remains at all times within the housing, thus preventing damage to the spring during use of the wrench.

As will be apparent from an inspection of the drawings, the pin 14 extends laterally through the head portion 2 and pivotally supports both of the movable jaws. By this construction it is only necessary to remove the single pin in order to completely disassemble the parts of the wrench for purposes of repair or replacement.

In using the invention as described above, a nut is inserted between the jaws in engagement with the notches 17 and 23, the jaw 4 being moved outwardly against the pressure of the spring 21. When the nut has been inserted as just described, the spring 21 maintains the jaw in firm contact with the nut, and presses the same into engagement with the jaw 5, so that the extension 9 is brought into contact with the abutment 8 on the head portion 2. The nut may then be applied in the usual manner by turning the wrench with the handle 1.

As seen in Figure 1 of the drawings, the jaw 4 is longer than the jaw 5, and the pivot point of the jaws is to the left of the center of the nut, indi-

cated in dotted lines. With the parts positioned as indicated, the relation of the pivot pin to the jaws is such that, upon a clockwise movement of the handle, the jaw 5 engages the abutment 8 and the jaw 4 moves in a direction to close the jaws firmly about the nut to tighten the same.

On the other hand, a movement of the handle in a counter-clockwise direction from the position indicated in Figure 1 causes the jaw 4 to be moved in a direction to open the jaws against the pressure of the spring 21, thus releasing the nut.

When it is desired to loosen the nut, it is only necessary to turn the wrench over so that the gripping action described becomes effective on a counter-clockwise movement of the handle.

By reason of the notches 17 and 23, and the movability of the jaws, a nut may be readily inserted in the wrench, the jaws 4 and 5 automatically adjusting themselves to grasp the nut.

It will be noted that the pivot pin 14 is located close to the opposed gripping portions of the pivoted jaws, and passes approximately through the longitudinal axis of the wrench, which results in obtaining a maximum of mechanical advantage with a minimum of strain on the parts.

It will thus be seen that the invention as above described provides a wrench which is efficient in operation, and is capable of use with a wide range of different types of fittings.

While the invention has been described in connection with a particular embodiment of the same, it will be understood that many changes can be made in the arrangement and proportions of the various parts within the skill of the mechanic, without departing from the scope of the appended claims.

Having thus clearly shown and described the invention, what is claimed as new and desired to secure by Letters Patent is:

1. A wrench, comprising a handle, laterally spaced extensions secured to the handle near one end of the same and having aligned apertures, a transverse rib connecting the spaced extensions near one side of the handle, the rib extending longitudinally forwardly of the aligned apertures and constituting a top, the rib being spaced longitudinally forwardly of the adjacent end of the handle for forming a transverse passage between the end of the handle and rib and between the longitudinal extensions, a pin mounted within the aligned apertures and extending between the spaced extensions and spaced laterally inwardly of the rib, a first jaw pivotally mounted upon the pin between the spaced extensions and extending longitudinally forwardly of the spaced extensions and having a part to engage the stop, the first jaw being swingable laterally and having an inner nut gripping side, a second jaw pivotally mounted upon the pin between the spaced extensions and having a forward curved extension projecting longitudinally forwardly of the free end

of the first jaw and having an inner nut gripping side, the nut gripping sides of the first and second jaws being disposed longitudinally forwardly of the spaced extensions, the second jaw including a longitudinally rearwardly projecting arm extending rearwardly of the rib and pin and disposed in the transverse passage, and a leaf spring secured to the side of the handle and having a part projecting into the transverse passage and contacting the rearwardly projecting arm of the second jaw, the spring serving to bias the forward end of the second jaw toward the first jaw.

2. A wrench, comprising a handle, laterally spaced plates secured to one end of the handle and having their outer faces substantially flush with the sides of the handle for forming a slender construction, the plates extending longitudinally forwardly of the adjacent end of the handle and being provided near their forward ends with aligned transverse apertures, the apertures being disposed substantially at the transverse center of the handle, a transverse rib connecting the spaced plates and being spaced forwardly of the forward end of the handle, the rib extending forwardly of the spaced plates to form a stop and being spaced laterally outwardly of the aligned apertures, a transverse pin mounted within the aligned apertures and extending between the spaced plates, a first generally longitudinal jaw pivotally mounted upon the pin between the spaced plates and extending forwardly of the plates and having a lateral shoulder near its forward end to contact the stop, the inner side of the first jaw being notched to form a nut gripping face, a companion jaw pivotally mounted upon the pin between the spaced plates and disposed laterally opposite the first jaw and swingable toward and away from the first jaw, the companion jaw having its inner side notched to form a companion nut gripping face, the nut gripping faces of the jaws being disposed forwardly of the spaced plates, a rear longitudinal extension carried by the companion jaw and extending rearwardly of the rib and into said passage, and a resilient element connected with the handle and disposed within the passage and contacting the rear longitudinal extension, the resilient element serving to urge the companion jaw toward the first jaw.
